(57) **CLAIM**

The ornamental design for an abdominal exercise device, as shown and described.

DESCRIPTION

FIG. 1 is a perspective view of an abdominal exercise device showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof;

FIG. 7 is a front elevation view thereof;

FIG. 8 is a perspective view of an abdominal exercise device showing our new design, with unclaimed environment removed for clarity of disclosure;

FIG. 9 is a top plan view thereof;

FIG. 10 is a bottom plan view thereof;

FIG. 11 is a right side elevation view thereof; and,

FIG. 12 is a left side elevation view thereof.

The broken lines illustrate environmental elements of the abdominal exercise device which form no part of the claimed design.
